UNITED STATES PATENT OFFICE.

WALTER J. CLOUTIER, OF ATTLEBORO, MASSACHUSETTS, ASSIGNOR TO J. M. FISHER COMPANY, OF ATTLEBORO, MASSACHUSETTS, A CORPORATION OF RHODE ISLAND.

DESIGN FOR A PATRIOTIC BADGE.

52,522.

Specification for Design.

Patented Oct. 8, 1918.

Application filed June 3, 1918. Serial No. 238,057. Term of patent 3½ years.

To all whom it may concern:

Be it known that I, WALTER J. CLOUTIER, a citizen of the United States, residing at the city of Attleboro, county of Bristol, Commonwealth of Massachusetts, have invented a new, original, and ornamental Design for a Patriotic Badge, of which the following is a specification, reference being had to the accompanying drawing, forming part thereof.

The design consists essentially of two banners connected by a pair of clasped hands.

The figure is a face view of a patriotic badge, illustrating my new design.

I claim:

The ornamental design for a patriotic badge, as shown and described.

WALTER J. CLOUTIER.
